HEATING SYSTEM FOR METAL BUILDING

Mills G. Clark, Cleveland Heights, Ohio, assignor,
by mesne assignments, to Insulated Steel Com-
struction Company, trustee, Cleveland, Ohio,
a corporation of Ohio

Application April 6, 1931, Serial No. 527,955

1 Claim. (Cl. 237—46)

This invention relates to metal building structures and more particularly to a heating system therefor. The type of building structure contemplated is one of sheet metal having hollow floors such as that shown in the copending application, Serial No. 511,967, filed January 29, 1931, by James E. A. Moore; and having the metal of its walls formed as disclosed in Patent 1,574,586 issued February 23, 1926 to J. F. Louks et al and known as "Holorib".

The floor has flooring and ceiling panels with parallel bracing webs extending therebetween throughout the floor width, so that the characteristic of the metal of the floor is a continuous repeated box section having through hollows between adjacent webs. The metal of the wall at that edge of the floor endwise of the webs thereof is disposed with the ribs running vertically and extending toward the floor, thus providing channels opening toward the floor hollows at the ends of the latter.

It is the object of my invention to provide such an association of the parts and to take advantage thereof in the provision of a heating system wherein hot air is supplied to the floor by way of the wall or a portion thereof, and return of the air to the heating means is had by way of another wall portion which may be of the same or the opposite wall. For this purpose I provide means bridging a pair or more of the ribs of the wall, above and below the floor to provide a wall riser conduit communicating with the floor hollow; and this is a further object of my invention.

Another object is the arrangement of a plurality of floors to be served by a pair of walls one on either side thereof, one taking warm air to the hollows of the floors, the other providing a return to the heating means, flow through the floors being generally parallel. It will be apparent that the system of heating is one wherein the building contents receive heat largely by way of the floors on which they are supported, and this, although ultimately by circulated hot air, is immediately largely by radiation from the floor area. That the floor area may have evenly distributed heat I provide as a further object of my invention that flow through a floor may be along a predetermined and generally devious path. To this end I provide openings in adjacent floor webs located adjacent opposite ends of the floor whereby the path will lead in opposite directions in adjacent hollows.

It will be appreciated that covering material

having heat insulating properties is applied to the metal of the structure to increase its thermal efficiency as a heating structure. Where the building structure includes an inner wall between two outer ones, it is a further object of my invention to arrange that the inner wall provide the riser for the hot air, and the return of the air be by way of the outer walls so that the flow is generally in a natural direction and with less heat losses in the outer walls. The exact nature of the invention together with further objects and advantages thereof will be apparent from the following description taken in connection with the accompanying illustrative drawings, in which Fig. 1 is a sectional elevation of an embodiment of my invention; Fig. 2 is a horizontal section as in the plane of line 2—2, Fig. 1, the section of Fig. 1 being as in the plane of line 1—1, Fig. 2; Figs. 3 and 4 are details in perspective showing the arrangement whereby hollows of the walls and floor are caused to communicate; Fig. 5 is a view similar to that of Fig. 2 but showing an alternate arrangement whereby the path of flow is elongated; Fig. 6 is a detail perspective showing an opening in one of the floor webs whereby the path indicated Fig. 5 is had; Figs. 7 and 8 are diagrammatic horizontal and sectional elevations respectively indicating a preferred arrangement where an inside wall is employed for a riser; and Fig. 9 is a detail section showing the support for the inside wall and the arrangement whereby warm air is introduced thereinto.

With reference now to Figs. 1—4 of the drawings, 1 represents the masonry foundation of a building on the four sides of which rest four side walls. The principal member 2 of each building side wall is of sheet metal bent as indicated Figs. 3 and 4 to provide hollow triangular ribs 3 extending vertically throughout the wall height, and turned toward the inside of the building. These walls may of course be in sections but if so the sections are made integral as by welding, as are the four walls at the corners of the building so that a rigid wall structure is had.

Within the four building walls is a floor. The principal floor structure is likewise of sheet metal comprising a plurality of lengths bent to Z-section and laid as indicated Figs. 3 and 4 each overlapping the other to form flooring and ceiling panels 4 and 5 respectively with parallel bracing webs 6 extending therebetween and each extending the width of the floor. The metal of the floor is supported on that of the walls as by

a number of angle irons 7 immediately above and below the floor and secured therewith and with the ribs 3 of the walls as by welding. The floor is, therefore, in effect rigidly integral with the walls. The structure may of course have any number of floors, one being shown.

It will be apparent that the floor has a number of hollows 9 one between each pair of webs 6, coextensive with the floor, and these hollows 10 are open-ended. Also the structure of the walls provides vertically extending channels between the ribs 3 thereof, of which channels riser conduits 10 may be made by securing metal panel plates 8 over any pair of ribs 3 as by welding. 15 As the hollows 9 open only at two sides of the floor, panel plates 8 are only useful to serve a floor at those sides thereof. If the panel plates extend only above and below a floor, the hollows 9 of the latter will obviously be in communicating relation with the risers 10 of the walls. If 20 a partition 11 be placed across one of the conduit risers at the top of a floor as in Fig. 4, all flow between riser and hollow must be to or from below the floor. But if instead a panel plate 8 25 be laid above the floor the corresponding riser will extend thereabove as to serve another higher floor while still communicating with the first floor. Thus as indicated in Figs. 1 and 2, a pair of closure members 12 are laid as indicated 30 to provide manifolds extending along below the floor at the edges adjacent the open ends of the hollows 9 thereof. A hot air furnace 13 has delivery connection as by the pipe 14 with one of these manifolds and return connection from the other by way of the pipe 15 and blower 16. 35 There is communication between the inlet manifold and all of the hollows 9 of the floor shown throughout the entire length of the wall. As indicated Fig. 4, partitions 11 are placed between some of the ribs 3 of the corresponding 40 wall just above the floor level so that flow is positively directed into the floor. On other parts of the wall, however, instead plates 8 are employed above the floor to form risers leading above the floor level and to the next floor. On 45 the opposite wall the arrangement is the same.

Thus a continuous passage for the heating medium is supplied by the furnace 13 across both floors in parallel relation, up one wall, through, and down the other wall therefrom, returning to the furnace by way of the blower.

To improve thermal efficiency, appearance and acoustical properties the metal of the structure is covered with a non-metallic insulating material as indicated. Wall channel portions 55 which are not used for heating conduits, are filled with this material as at 17 in an amount sufficient that some of the material overlies the plates 8 as at 18 to present a smooth interior wall surface. A thickness of the material as at 19 is applied to the outside wall surface, as is a 60 ceiling thickness beneath the floor indicated at 20. The floor is overlaid by a denser material as at 21.

It will thus be apparent that a closed path is 65 provided for the heating medium which path includes all of the floor areas and part of the wall areas. The conduit dimensions, therefore, while slight in one direction, are so extensive in the other that the sectional area for path of 70 flow is ample for all conditions. Moreover, no room space is taken up by any part of the heat-

ing system. While air may be employed as the primary medium of heat transfer, this air is recirculated in a closed path so that impurities from the outside are not introduced into the inside thereby.

The arrangement described will be recognized as more or less elementary. In many instances as where heat is to be delivered through a single floor, it is desirable to provide a deviaceous path through the floor. An arrangement for this purpose is shown Figs. 5 and 6 wherein air is introduced into one end of one of the end hollows of the floor as at 22 and return connection is had at one end of the hollow at the opposite end of the floor as at 23. The other ends of the hollows are closed by partitions 24. Openings 25 are provided in the webs 6 of the floor. The openings may be located at opposite ends of alternate webs as indicated in Fig. 5, so that the path of flow through the floor will be as shown by the arrows.

Frequently the building structure will include an inside wall 26 between outside walls 27 as indicated in Figs. 7 and 8. Here it is preferable that the heating risers be associated with the inside wall and the return risers with the outside walls so that the direction of flow will be as indicated by the arrows in Fig. 8. Fig. 9 shows a manner of supporting the inside wall which permits introduction of air thereto entirely therealong. 28 is a beam upon which the inside wall is supported, the wall having the first adjacent floor level slightly above the beam. At one end of the wall as at 29 the ribs 3 thereof are turned to the right as appears in Fig. 9 so that by a short 10 closure member 12a a path may be had from the manifold provided into the floor portion toward the right. At the other end of the wall as at 12b the ribs are turned in the other direction and the manifold 12b similarly provides for introduction 115 of heating air to the left-hand floor portion. The two floor portions have outlets at 30 and their webs 6 have openings 25 so that flow through the floor portions will be as indicated by the arrows in Fig. 7 and the arrangement will provide a 120 deviaceous path generally similar to that Figs. 5 and 6.

By the employment of panel plates 8 as directed in connection with Figs. 1 and 2, provision may be made for heating additional overhead floors 125 in a manner which will be apparent.

What I claim is:

Building construction of the class described comprising a sheet metal floor panel, the panel comprising a plurality of sheet metal units of 130 coextensive length assembled to provide a continuous repeated box section having spaced top and bottom faces with webs extending therebetween, a wall panel at the end of said floor panel and comprising a sheet metal part secured with 135 said floor panel and deformed to provide vertically extending channels opening toward said floor panel and there communicating with cavities of the latter, said wall panel including non-metallic parts overlaid upon said sheet metal 140 parts to close said channels on the corresponding side of said floor panel and thereby provide conduit passage means effective to conduct a heating medium between the hollows of said panels.
